UNITED STATES PATENT OFFICE.

SIDNEY SCHNEIDER, OF CHICAGO, ILLINOIS.

STUD-SETTING TOOL.

1,125,186.

Specification of Letters Patent.

Patented Jan. 19, 1915.

Application filed February 13, 1913. Serial No. 748,072.

To all whom it may concern:

Be it known that I, SIDNEY SCHNEIDER, a citizen of the United States, residing at Chicago, Cook county, Illinois, have invented certain new and useful Improvements in Stud-Setting Tools, of which the following is a specification.

My invention relates to improvements in tools, and has more particular reference to tools for setting or fastening studs.

One of the objects of my invention is to provide an improved tool of this character which will be simple, durable and reliable in construction, and effective and efficient in operation.

Another object of my invention is to provide an improved stud-setting tool by which threaded studs and the like may be easily, quickly and firmly set or screwed into place without damage to the studs; my purpose being to provide an improved tool which will firmly hold or grip the stud or like member during the act of setting or fastening the stud, but will instantly release its hold without "backing out" or loosening the stud, while the tool is being detached or removed.

A further object of my invention is to provide an improved tool of the character which may have a set of various sized jaws or adapters for different size studs, and may be sold on the market as a stock or standard tool for the purpose.

Other objects of my invention will appear hereinafter.

My invention consists in the features of novelty exemplified in the construction, combination and arrangement of parts herein described, and shown in the accompanying drawings which illustrate one embodiment of my invention, and more particularly pointed out in the appended claims.

In the drawings, Figure 1 is a disassembled view, partly in elevation, and partly in section, of the parts of a structure embodying my invention. Fig. 2 is an assembled view partly in section, showing the tool in the act of setting a stud. Fig. 3 is a similar view of the main portion of the tool just after having released its hold on the stud to permit its removal therefrom. Fig. 4 is a perspective view of one of the jaw sockets or adapters, and Fig. 5 is a transverse sectional view on the line 5—5 of Fig. 2.

In the drawings I have illustrated my in-

vention as embodied in a tool more especially designed for setting studs threaded at both ends, but it will be obvious, to one skilled in the art, after having obtained an understanding of my invention from the disclosures herein made, that the principles and functions of my invention may be embodied in other structures designed according to the particular conditions and requirements to be met, without departing from the scope and spirit of the invention. The stud A illustrated in the drawing is intended as representative of the various articles or members of this character, and the plate B illustrated is likewise representative of any member or part to which a stud is to be fastened. The stud A as will be noticed is threaded at both ends. The threaded end A¹ serves as a means of holding it in a threaded hole in the plate B or other member, and the threaded end A² serves as a means by which a machine element or other member may be attached or anchored to the stud. Studs of this character are difficult to set in the plate or member B, for the reason that either a sufficient grip cannot be obtained on the threaded end A² without stripping or damaging the threads, or when a tool having a threaded socket is used, the act of unscrewing said tool "backs off" or unscrews the stud from the member A, this being obvious since the stud becomes set as tight in the tool as in the plate.

A tool constructed in accordance with my invention has an element or member which is adapted to be mounted on the stud to be set, and which, in conjunction with another element or elements, operates during the setting operation to tightly grip and hold the stud. However, in removing or detaching the tool the elements immediately act relatively to each other and to the stud to release their hold upon the stud and permit the tool to be freely detached without straining or loosening the stud.

In the structure shown in the drawing the member or element which is mountable on the stud is represented by a hollow sleeve or socket member C, the lower portion C¹ of the bore of which is threaded to receive the correspondingly threaded end A² of the stud, and the upper portion C² of which is enlarged to form, in a sense, a bearing for a cylindrical portion D¹ of a shank or mandrel D. In practice I provide a number of

these sockets with each tool. Their threaded portions which receive the studs vary in accordance with the different size studs, but their portions which receive the shank portion D¹ are uniform so as to be interchangeable. The shank D has a tongue D² projecting from the bearing portion D¹ and this tongue is reduced in diameter so that it will rotatably fit into the upper end of 5 the partially threaded portion C¹ of the socket member. These parts are preferably so proportioned that the end of the tongue and of the stud meet at about the middle of the stud bore C¹ of the socket member, as clearly shown in Figs. 2 and 3, and the end portion D³ of the tongue is still further reduced so as to contact with or engage the end of the stud and not interfere with the threads. The shank D at the base of the 10 bearing portion D¹ is enlarged to a diameter substantially equal to that of the socket member, so that its surface is flush therewith, and a shoulder D⁴ is thereby formed. The shank portion D¹ has a laterally projecting pin D⁵ which, when the parts are 15 assembled, plays in a circumferential slot D⁶ in the upper portion C² of the jaw or adapter C. This arrangement provides for a certain relative rotative movement between 20 the shank and the socket or adapter member C.

The structure illustrated has been designed more particularly for setting right-hand threaded studs, although it is obvious 25 that my invention is not so limited, and that the requirements and conditions to be met are determining factors in the design of a setting tool of this character. The slot D⁶ is pitched or inclined at an angle to the 30 longitudinal axis of the stud and tool, as shown clearly. It may follow a progressive spiral, and since this structure is adapted for right-handed studs, the pitch of the stud is lefthanded, that is, away from the stud 35 in a left-handed direction of rotation of the shank D. The slot thus presents a cam, so to speak, to the pin D⁵ which causes a relative longitudinal movement of the shank D and socket C when they are relatively rotated. Hence in this structure it will be seen 40 that by rotating the shank right-handedly the socket member will likewise be rotated by the pin D⁵, engaging the end C⁴ of the slot D⁶. The elements acting in conjunction 45 in this manner carry the stud therewith and screw it into the plate. The tool may be turned thus until the stud has been very tightly set in the plate. This is true since the end portion D³ of the tongue blocks or 50 prevents the stud from screwing into the socket member only so far (Fig. 2). Thus the tool obtains a firm setting grip on the stud without injuring the threads thereof, but there is a tendency for the stud to screw 55 very tightly into the socket member. How-

ever, after the stud has been tightly set in the plate the tool, a slight reverse rotation, instantly releases its grip upon the stud. This is apparent for the reason that on account of the cam slot D⁶ and the pin D⁵, the shank and portion D¹ move longitudinally away from the stud the instant the stud is given a reverse rotation relatively to the socket member as shown clearly in Fig. 3. This instantly releases the tool from the stud without imparting the least "unscrewing" or loosening strain upon the stud. The relative reverse rotation of the shank need be just sufficient to relieve the hold on the stud and accordingly the length and pitch of slot D⁶ may be just sufficient for this purpose. In this structure I have found about a half-turn is sufficient for this purpose. Hence, I have made the slot long enough to permit about a half-turn of the pin D⁵. The reverse movement of the shank to release the hold upon the stud may be continued until the pin strikes the slot-end C⁵, and since by this time the tongue has sufficiently backed off or away from the stud, both members or elements of the tool may be freely rotated together and removed or disconnected from the stud without straining the stud or loosening it in the least.

In order that the socket members of various sizes may be interchanged as desired, their slots D⁶ have openings or entrances D⁷ for the pin D⁵. I guard against the accidental separation of the socket and shank by means of a movable or slid able sleeve 100 member F which may be shifted to a position to cover the pin and slot and adjacent parts. This sleeve has a slot F¹ which cooperates with a small pin F² on the socket members. This slot has an entrance opening F³ for pin F². After the socket member has been slipped on the shank, the sleeve F is shifted down until the pin F² enters slot F¹. It is then rotated until the entrance opening F³ is moved out of relative position 105 with respect to the range of movement of pin D⁵ in slot D⁶. In this position the sleeve is yieldingly locked by a spring catch which may consist of a small spring-pressed ball H arranged to engage a small hole H¹ in the 110 sleeve. Any suitable means may be employed for rotating the tool. The shank may, if desired, be formed for use in a lathe. We have, however, shown it provided with a transverse handle S and a squared end S¹ 115 120 for the purpose of conveniently operating it.

What I claim as new is:

1. In a tool of the class described, the combination of a threaded socket member having an open-ended cam slot, a shank member extending into said socket member, means on said shank member playing in said slot for longitudinally moving said shank member in said socket member when the shank is rotated in one direction, said 13

means being adapted to be passed through the open end of said slot to separate and assemble said socket member and shank.

2. The combination of an internally threaded socket member adapted to fit the stud to be set and having a cam slot in its periphery inclined with respect to the axis of said socket member, said cam slot having an opening, a shank member rotatable within said socket member with its end in position to engage the end of the stud in the socket, and a pin on said shank member

adapted to be passed through said opening 13 and to play in said cam slot whereby the shank member and socket member may be readily separated and assembled.

In testimony whereof I have signed my name to this specification, in the presence of two subscribing witnesses, on this 19th day of Sept. A. D. 1912.
